M. COOPER

LOW QUARTER SHOE

Filed March 18, 1924

*1 Inventor
Morris Cooper
by his Attorneys
Baldwin Wright.*

UNITED STATES PATENT OFFICE.

MORRIS COOPER, OF BALTIMORE, MARYLAND.

LOW-QUARTER SHOE.

Application filed March 18, 1924. Serial No. 700,040.

To all whom it may concern:

Be it known that I, MORRIS COOPER, a citizen of the United States, and resident of the city of Baltimore, and State of Maryland, have invented certain new and useful Improvements in Low-Quarter Shoes, of which the following is a specification.

This invention relates to a low quarter shoe in which the entire upper is made of three parts of such shape that when properly joined they will form a neat and well fitting shoe of pleasing appearance which dispenses with the use of the usual buttons or laces.

An object of the invention is to employ a strap as the fastening means, which strap is made integral with the vamp portion and passes from the inside of the shoe over the instep under the ankle to a buckle located on the outside quarter well toward the rear of the shoe and below the ankle.

Another object of the invention is to have the outside quarter overlap the inside quarter on the instep slightly to the inside of the center line and to have the strap pass over the overlapping portions in such a manner as to tightly close the opening.

Another object of the invention is to stitch the strap to the inside quarter at a point adjacent the overlapping edge of the outside quarter in order that the parts may fit smoothly and neatly over the instep.

Other objects will be apparent from the following detailed description and the appended claims.

35 In the drawings:

Figure 1 is a perspective view of the front and outside of a right shoe.

Figure 2 is a similar view of the front and inside of a right shoe.

40 Figure 3 is a plan of the blank for the vamp.

Figure 4 is a plan of the blank for the inside quarter.

45 Figure 5 is a plan of the blank for the outside quarter.

The shoe forming the object of this invention has an upper formed of three portions, and employs no tongues, buttons, laces or elastic. The usual sole and heel may be employed and the parts forming the upper may be fastened thereto in the usual or any suitable manner.

50 The blanks for the three portions of the upper have the form indicated in Figures 3, 4 and 5, and comprise a vamp A, an outside quarter B and an inside quarter C.

The outside quarter B has an edge 1-2 which is joined at the back of the shoe to the corresponding edge of the inside quarter in any usual or desired manner; a curved edge 2-3 forming the top edge of the outside of the shoe; an edge 3-5 which overlaps the meeting edge of inside quarter along a line to the inside of the center line of the foot, which edge has a cut out 4; a straight edge 5-6 and a curved edge 6-7 which is overlapped by the vamp; and a straight edge 7-1 which is attached to the sole and heel.

The inside quarter C has an edge 8-9 which is joined at the back of the shoe to the edge 1-2 of the outside quarter; an edge 9-10 forming the top edge of the inside of the shoe; an edge 10-12 with a cut out 11 which is overlapped by the corresponding portion of the outside quarter; a straight edge 12-13 and a curved edge 13-14 which is overlapped by the vamp; and a straight edge 14-8 which is attached to the sole and heel.

The vamp A, shown in Figure 3, has a free edge 15-16 which is attached to the quarter B by a row of stitching *a* which stitching extends around the curved line to the point 17 and part way up the strap as shown in Figures 1 and 2, thus stitching the vamp to both quarters. The outer edge 15-20-21 of the vamp is attached to the sole of the shoe. The strap portion D integral with the vamp is attached to the inside quarter C by a line of stitching *b* at a distance from the overlapping edges of the two quarters which may be varied as desired depending upon the precise conformation of the foot of the person for which the shoe is made. The free end 18-19 of the strap is designed to pass through a buckle E carried by the outside quarter at a point well beneath the ankle and toward the rear of the shoe. The outside edge of the strap from the sole at the point 21 is stitched to the inside quarter by a line of stitching *c* which extends up to the stitching *b*.

The front and overlapping portions of the two quarters are stitched together at 40 *d* for a short distance up from the line of stitching *a*, this distance depending upon various considerations. The remainder of the distance allows for the opening of the shoe when putting it on or removing it.

It will be noted that by having the outside quarter overlap the inside and having the

strap extend upward from the inside of the shoe across the overlapping portions around under the ankle to a point of fastening well toward the rear, the upper is caused to fit smoothly and snugly over the instep and any slipping up and down of the foot in the shoe is prevented. Not only does the shoe fit snugly over the instep, but there is no opening which may admit snow, water or dust as in the case of the usual shoe having a tongue over which the quarters lap. Furthermore, the strap is integral with the vamp and extends directly from the point of attachment to the sole up and over the instep. This will tend to support the arch of the foot and be beneficial to the wearer as well as pleasing in appearance and comfortable in feeling. The strap will, of course, be provided with a plurality of holes for adjustment.

The shoes can be manufactured with a minimum of labor, since the lines of stitching *a*, *b* and *c* are continuous, and the line *d* is short. These lines of stitching, together with the usual joining of the quarters in the rear, comprise the entire means whereby the portions of the upper are attached to each other.

A right shoe has been illustrated, but for the left, there is simply necessary the obvious change in form of the blanks. It is evident that modifications may be made in the precise form without in any way departing from the spirit of the invention, and it is to be understood that the invention is to be regarded as limited only by the scope of the appended claims.

I claim as my invention:

1. A shoe having an upper formed of three pieces, an inner quarter, an outer

quarter overlapping the inner at the front and attached thereto for a part of the extent of the overlapping, and a vamp attached to each of the quarters and having a strap integral therewith at the inner side which passes over the overlapped portions and rearwardly to a point of attachment to the outer quarter which is located considerably to the rear of the instep and below the top of the shoe.

2. A shoe having an upper formed of three pieces, an inner quarter, an outer quarter overlapping the inner at the front and attached thereto for a part of the extent of overlapping, and a vamp attached to each of the quarters and having a strap integral therewith at the inner side which is attached to the inner quarter up to a point near the overlapped edge of the quarter and extends over the instep and rearwardly to a point of attachment to the outer quarter which is located well to the rear and below the top of the shoe.

3. A shoe having an upper formed of three pieces, an inner quarter, an outer quarter attached thereto at the rear and overlapping the inner at the front, a portion of the overlapping edges being attached to each other by stitching, and a vamp stitched to each of the quarters and having an integral strap at the inner side which is stitched to the inner quarter at a point adjacent the overlapped edge of the outer quarter, and then extends rearwardly and downwardly over the instep to a point of attachment to the outer quarter which is located below and to the rear of the ankle bone.

In testimony whereof, I have hereunto subscribed my name.

MORRIS COOPER.
